UNITED STATES PATENT OFFICE.

AUGUST HARALSON AND GUSTAF R. ANDERSON, OF MINNEAPOLIS, MINNESOTA; SAID ANDERSON ASSIGNOR TO SAID HARALSON.

SOFA-BEDSTEAD.

SPECIFICATION forming part of Letters Patent No. 351,029, dated October 19, 1886.

Application filed March 23, 1886. Serial No. 196,267. (No model.)

To all whom it may concern:

Be it known that we, AUGUST HARALSON and GUSTAF R. ANDERSON, citizens of the United States, residing at Minneapolis, in the county of Hennepin and State of Minnesota, have invented certain new and useful Improvements in Sofa-Bedsteads; and we do hereby declare the following to be a full, clear, and exact description of the invention, such as will enable others skilled in the art to which it appertains to make and use the same.

This invention relates to that class of household furniture known as "sofa-bedsteads;" and it consists in certain improvements in the construction of the same and novel combinations of parts, which will be hereinafter fully described and claimed.

According to our invention, the sofa-bedstead is provided with two mattresses, the upper of which is provided with a double series of springs, the one series arranged above the other. The upper mattress is upholstered on both its upper and lower sides, and is hinged to the frame of the lower mattress, so that when opened to form a bed the lower side of the upper mattress will form a continuous spring surface with the upper side of the lower mattress.

The frame of the sofa is combined with a drawer, which forms a receptacle for the bed-clothing, and when drawn out a frame for the support of the upper mattress.

In the accompanying drawings, in which corresponding parts are designated by similar letters, Figure 1 is a perspective view showing the parts open. Fig. 2 illustrates in perspective the position of the drawer. Fig. 3 is a transverse vertical section; Fig. 4, a longitudi-

nal vertical section, and Fig. 5 a perspective view of the drawer.

The main frame of the sofa is provided with solid ends A A', and a back piece, B, extending entirely to the floor, and the mattress parts of two sections, the upper of which, C, contains two sets of coiled springs, the one set, a, arranged above the other, a', and the lower of which, D, contains one set, d. When thrown apart, as shown in Fig. 1, the two sections form a continuous bed of coiled springs without any ridge or cross-piece between them, and when closed, as shown in Fig. 2, as the upper portion of the upper section is well provided with springs, a comfortable sofa is constructed.

The drawer E is provided with slides e, by means of which it may be moved in or out, and when drawn out it forms a receptacle for the upper section, as shown in Fig. 1.

Having thus described our invention, we claim and desire to secure by Letters Pat- ent-

In a sofa-bedstead, the combination of the upper mattress containing two sets of springs, a a', the lower mattress, D, the drawer E, provided with slides e, sliding in grooves on the inner side of the end pieces, A A', and extending through openings in the back piece, for supporting it when closed, as and for the purpose described.

In testimony whereof we affix our signatures in presence of two witnesses.

AUGUST HARALSON.
GUSTAF R. ANDERSON.

Witnesses:

F. A. BISHOP,
C. G. LAYBOURN.
